UNITED STATES PATENT OFFICE.

ROBERT SCOTT, OF HONOLULU, TERRITORY OF HAWAII.

MACHINE FOR CONVEYING AND LOADING CROPS OR MERCHANDISE.

SPECIFICATION forming part of Letters Patent No. 718,732, dated January 20, 1903.

Application filed February 8, 1902. Serial No. 93,200. (No model.)

To all whom it may concern:

Be it known that I, ROBERT SCOTT, a citizen of the United States, residing at Honolulu, Island of Oahu, Territory of Hawaii, 5 have invented certain new and useful Improvements in Machines for Conveying and Loading Crops or Merchandise; and I hereby declare the following to be a full, clear, and exact description of the invention, such as 10 will enable others skilled in the art to which it appertains to make and use the same.

My invention is designed principally for use in sugar-cane fields, and it is intended to receive the sugar-cane as it is cut by the laborers and convey it to a car located near the 15 machine.

The object of my invention is to produce a simple, inexpensive, portable, easily-operated labor-saving machine. I employ either two 20 or four arms pivoted at the center, capable of being moved in a horizontal plane about their common pivot. Each pair of arms is rigidly connected together at the center of the machine and braced, so as to be in line 25 with each other. When four arms are used, the pairs of arms are placed at right angles to each other. Each pair of arms is capable of being moved in a vertical plane, like a seesaw, independent of the other pair. The 30 pivot is supported either by an adjustable tripod or other suitable arrangement upon the ground, and the machine, which is light, is carried by hand from one position in the field to another when necessary, or the machine may be located on a car or wagon. Attached to the arms is a track carrying a trolley that is capable of being moved in or out along the arm toward or from the pivot of the machine. The cane to be loaded is first cut 35 and then laid upon slings placed upon the ground or on a cradle. The ends of a loaded sling are then attached to the trolley by depressing the arm of the machine brought over the sling. A man at the opposite arm then 40 depresses his arm, thereby raising the sling loaded with cane, which becomes suspended on the trolley of the arm opposite the operator. The machine is then turned, if necessary, and the sling is moved in or out on its 45 trolley-track until it is over the car to be loaded. The cane is then dropped into the car, as will hereinafter more fully appear.

In the accompanying drawings, Figure 1 represents an elevation of one-half of a two-arm machine with tripod, trolley and its track, 55 and the vertical stay with its struts. Fig. 1^a represents, on a somewhat larger scale, an end view of the connecting-piece between the two main track-sections and illustrates its relation to the main transverse arm of the machine. Fig. 1^b represents a view of said connecting-track at its point of suspension from the tripod and shows in dotted lines the location of a permanent support sometimes contemplated by me. Fig. 2 represents, on a 60 smaller scale, a plan of the arms of a four-arm machine with the horizontal bob-stays. Fig. 3 shows, on a larger scale, the swinging joint of a four-arm machine. Fig. 4 represents, in elevation and part section, the joint 70 at the center of the first pair of arms and the pivot arrangement. Fig. 5 represents the method of connecting the pipes forming the arm.

Similar letters of reference indicate similar 75 parts throughout the several views.

Referring to the drawings, it will be noted that the machine as a whole is of light but strong construction.

The arm A, Fig. 1, is preferably made up 80 of different sizes of pipe a' a² a³, telescoping each other. One of these joints is shown in Fig. 5. A split collar w' is secured inside the pipe a' and is tapered inside to receive the end of the pipe a³, while another split collar 85 w², fitting the pipe a², is tapered outside to wedge the end of the pipe a'. Collars b' b² are clamped at the joints and are provided with a boss to secure the struts c² c³, Fig. 1, to the overhead or vertical bob-stay d. The 90 largest-size pipe a' at the center of the machine is in one piece and is common to both arms A and B and has a hole through its center, through which the pivot f is free to operate. The trolley-track g g' is secured to 95 the arms at intervals, and a connecting-piece g² may be used to connect the tracks g and g' together when desired to run the trolley from one arm to its mate. It will be understood that it is necessary that the pivot be 100 located at a suitable height from the ground. As shown more fully in Fig. 1^b, the pivot referred to consists of a continuation of the end of the pin f, which continuation passes

through a supporting-hanger g^6 , said hanger being held in place by nuts screwed upon the screw-threaded end of the continuation of the pin f . The continuation of the pin f 5 passes through an aperture in the hanger and permits the hanger to swing horizontally to the extent permitted by the legs of the tripod through which it passes. The connecting-piece g^2 is likewise adapted to swing vertically or tilt upon the hanger g^6 as a center. At the outer ends of the connecting-piece g^2 10 are attached the spring-stops g^4 , having at their upper ends the rounded portions g^5 , which are adapted to catch under or engage with the under side of the pipe a' , so that the connecting-piece will rock with the arms A B and with the tracks d d' . When the arms A B are moved in a horizontal plane, the connecting-piece g^2 will travel with them until 15 it comes in contact with the obstructing leg of the tripod, whereupon the spring-pieces g^4 will release their hold upon the pipe a' . The operator applies his weight to a stirrup h , which is adjustably suspended from a wheel 20 j on the outer end of the arm, and he may use different lever-arms by shifting the position of the wheel j by the use of the rope k , passing through the blocks k' k^2 , or he may operate it simply by a rope attached to the 25 end of the arm, or, as illustrated in dotted lines in Fig. 1, the stirrup and its operating mechanism may be located upon the track instead of being located upon the arm above it.

When four arms are used, the arms C and 30 D, Fig. 2, are securely fastened to castings l' l^2 , (shown in Fig. 3,) which are bolted together over arms A and B and straddle the casting m at the center of the machine. While l' and l^2 are bolted together tightly, 35 they do not tightly grip the pipe a' of arms A and B, but permit the arms C and D to move in a vertical plane about the axis of the pipe a' . The castings l' and l^2 may be provided with roller-bearings and the pipe a' 40 provided with wearing-bushings. A boss is provided on l' and l^2 , (shown at n' and n^2 in Fig. 3,) each to carry a pipe-strut, these two struts being slightly longer than the center strut c' , attached to m , in order that the vertical bob-stays may clear each other. Side 45 bob-stays are shown in Fig. 2, the inner ends being fastened to clips r' r^2 for arms A B and to the castings l' l^2 at p' p^2 , &c., for arms C and D, as shown in Fig. 3.

In order to bring the center of gravity of the 50 machine below the point of suspension, a casting m , Fig. 4, in the form of a cross is used. This fits snugly over pipe a' and has a cap q screwed into its upper branch. The strut- 55 pipe c' is screwed into this cap and a hardened-steel cup r is secured underneath. The upper end of the steel pin f is rounded and hardened and fits the cup r . This pin f is tapered near its lower end to fit the tripod- 60 head. The lower branch of the cross m is partly filled with metal, (shown in section, Fig. 4,) so as to leave an oblong opening for

the pin f and allow the arms A and B to tip only in a vertical plane. The bearing may be made dust-proof by employing a felt or 70 other suitable washer, as shown in Fig. 4. This opening may be provided with roller-bearings. A drum or winch arrangement may be attached to the tripod and a snatch-block attached to the arm in place of the trolley arrangement for lifting the loaded slings. 75

To facilitate operations, I preferably employ a detachable sling—as shown, for instance, in Fig. 1—which may be made in two parts which are easily coupled or uncoupled. 80 This sling is laid upon the ground or on a cradle and the cane is piled upon it—say a hundred pounds for a load. After receiving the load it is placed over the hook g^3 of the trolley, and by the operation of the machine 85 already described the loaded sling is brought over the car to be loaded and the cane is discharged.

The arms in practice are each made about thirty feet long. Two machines may be placed 90 with pivots about sixty-one feet apart and connected together by a short piece of pipe slipped into the pipes forming the outer ends of one arm of each machine, and with a short rail connecting the trolleys the load can be 95 shifted from one machine to the other. As indicated in Fig. 1^b, the lower end of the pin f may screw into a pipe-stand suitably anchored in place, so as to sustain the weight 100 of the machine, in lieu of a tripod. Moreover, the lower or pointed ends of the tripod may serve as pistons to the upper portions thereof, and the cross-pipes a' or b , or both, may constitute reservoirs of compressed 105 air in whole or in part, which air may be admitted into the hollow legs of the tripod simultaneously by means of the branch tube x , (shown in Fig. 1,) adapted to connect with the nipples shown upon the tripod-legs. By admitting compressed air into the legs of 110 the tripod the upper part of said tripod will be lifted to raise the beam to any desired height, and by permitting the air to escape from the tripod-legs the tripod will be lowered 115 correspondingly. By this means the beam carried by the tripod may be adjusted to such heights as the operator may find necessary.

A spring-catch y (see Fig. 1) may be clamped upon the track at any desired point, so as to 120 permit the trolley to pass over it in one direction, but which will not permit it to return until removed or depressed for that purpose.

Having thus fully described my invention, what I claim as new, and desire to secure by Letters Patent, is—

1. A machine for conveying and loading crops and the like, comprising oppositely-extending arms capable of being tilted vertically, and rotated horizontally about a common central pivot, and a track supported by 130 said arms and adapted to support a trolley running lengthwise of said arms; substantially as described.

2. A machine for conveying and loading

- 5 crops and the like, comprising oppositely-extending arms made of jointed pipe-sections supported on a central pivot and capable of being tilted upon and rotated about said pivot, and a track supported by said arms and adapted to support a trolley running lengthwise of said arms; substantially as described.
- 10 3. A machine for conveying and loading crops and the like, comprising oppositely-extending arms capable of being tilted and rotated, and a track suspended from said arms and carrying a trolley to which the load is attached; substantially as described.
- 15 4. A machine for conveying and loading crops and the like, comprising a base or standard, oppositely-extending arms mounted on said standard and capable of being tilted and rotated horizontally thereon, track-sections carried by the respective arms, and a track-section carried by said standard to connect the sections on the arms; substantially as described.
- 20 5. A machine for conveying and loading crops and the like, comprising a base or standard, a beam formed of telescoping pipe-sections centrally pivoted upon said standard and capable of being tilted and rotated horizontally thereon, and a track connected by brackets to said beam to receive and convey a load-supporting trolley from end to end of said beam.
- 25 6. A machine for conveying and loading crops and the like, comprising a base or standard having a fulcrum or pivot-pin, a beam centrally pivoted upon said pin, track-sections, connected by brackets to the respective arms of said beam, an intermediate track-section secured to said pivot-pin, and means for normally holding said intermediate section in alignment with the other track-sections.
- 30 7. A machine for conveying and loading crops and the like, comprising a standard, a fulcrum or pivot secured in the top thereof, a beam centrally pivoted on said pin, depending track-sections secured to the arms of said beam on each side of the pivotal point, an intermediate track-section connected intermediate of its ends to said pin, and spring-stops secured to said intermediate section and engaging the respective beam-arms serving to hold the intermediate track-section in alignment with the beam track-section, substantially as described.
- 35 8. A machine for conveying and loading crops and the like, comprising a standard, a fulcrum or pivot-pin secured in the top thereof, a beam centrally pivoted on said pin, said beam comprising two arms formed of telescoping pipe-sections, depending track-sections secured by brackets to the respective beam-arms, an intermediate track-section pivoted to a bracket revoluble on said pivot-pin, and spring-stops secured to said intermediate track-section and engaging the respective beam-arms serving to hold the intermediate track-section in alignment with the beam track-sections; substantially as described.
- 40 9. A machine for conveying and loading crops and the like, comprising a standard, a fulcrum or pivot-pin secured to the top thereof, a beam centrally pivoted on said pin, said beam comprising two arms formed of telescoping pipe-sections, and an intermediate member by which the beam is supported on the pivot-pin to permit a rocking and rotary movement of said beam, depending track-sections secured by brackets to the respective beam-arms, an intermediate track-section connected to said pivot-pin, and means for detachably securing said intermediate track-section to the respective beam-arms to maintain the latter in alignment with the other track-sections, substantially as described.
- 45 10. A machine for conveying and loading crops and the like, comprising a hollow standard formed of telescoping sections, a beam centrally pivoted on said standard and capable of being tilted vertically and rotated horizontally on said standard, and means for adjusting said standard comprising a source of fluid-pressure, connections between the pressure source and said hollow standard to admit pressure to said standard to elevate the latter, and means to relieve the pressure in said standard to lower the same; substantially as described.
- 50 11. A machine for conveying and loading crops and the like, comprising a hollow standard formed of telescoping sections, a hollow beam containing fluid under pressure, said beam being centrally pivoted on said standard and capable of being tilted vertically and rotated horizontally on said standard, a tubular connection adapted to establish communication between said hollow beam and said hollow standard to elevate the latter by fluid-pressure, and a valve in said standard to relieve the pressure in the latter to lower the same; substantially as described.
- 55 In testimony whereof I have signed my name to this specification in the presence of two subscribing witnesses.

ROBERT SCOTT.
